UNITED STATES PATENT OFFICE.

LIPMAN HENSCHEL, OF NEW YORK, N. Y.

HAT-COVERING.

1,293,645.

Specification of Letters Patent.

Patented Feb. 4, 1919.

Application filed February 14, 1918. Serial No. 217,222.

To all whom it may concern:

Be it known that I, LIPMAN HENSCHEL, a citizen of the United States, residing at New York, in the county of New York and State of New York, have invented new and useful Improvements in Hat-Coverings, of which the following is a specification.

This invention relates to coverings for head-gear, and the principal object of the same is the provision of a water-proofed covering or hood which is adapted to be applied snugly upon various types of hats in order to protect the same against rains, storms, or otherwise injurious conditions.

Another object of the invention is the provision of a water-proofed covering or hood of this character which is adapted, when not in service, to be conveniently carried within the hat, the pocket, or hand bag, which can be quickly and readily applied when needed, and which is constructed so as to be conveniently adjustable for application to hats differing in type and size.

With these and other objects in view, the invention resides in the details of construction and in the arrangement and combination of parts hereinafter described and shown in the accompanying drawings, forming a part of this specification, and in

Figure 1 is a view in perspective, showing my covering applied to a hat.

Fig. 2 is a similar view with the hat in inverted position.

Fig. 3 is an elevational view, partly diagrammatic and partly in section.

Fig. 4 is a fragmental view, showing how the parts are seamed together against the seepage of water, and to enable adjustment.

Fig. 5 is a fragmental sectional view, showing another method of seaming the parts together while providing for similar adjustment.

Fig. 6 is a fragmental perspective view, illustrating a modified method for providing adjustment upon the underside of the brim.

With more particular reference to the accompanying drawings, the character 10 is employed to denote a side-crown piece, which is seamed together at 11, and which, between its front and back regions, has its top-crown portions preferably extended or expanded to provide gently incurved confronting sides 12, as best shown in Fig. 1. To complete the top of the covering, a crown-piece 13

preferably elongated, as shown, is seamed at 14 to the side-crown therearound.

Seamed at 15 around the lower edge of the side-crown is the brim piece 16, which is seamed together at 17, and which terminates at its outer edge in a looped or folded edge 18, designed to provide for suitable expansion or contraction so as to be capable of being drawn over brims of different types and sizes. Around the underneath side of the looped edge 18, as best indicated in Fig. 3, is attached an elastic element 19, the purpose of which is to hold the outer portion of the brim piece 16 drawn tightly upon the underside of the hat brim, and which is designed as well to hold the covering snugly upon the hat against accidental removal. As illustrated in Fig. 6, instead of employing the elastic element 19, the seam 17 may terminate short of the outer edge of the brim portion 16, which in this form, is provided with an over-lapping flap portion 20, the parts then being detachably secured together by a snap fastener as 21.

All of the foregoing constituent pieces are made of light, flexible, water-proofed material, such as water-proofed silk, although other suitable material may be employed. To preclude seepage of water and to provide for relative adjustment, all the pieces are preferably seamed together in overlapping position. As shown in Fig. 4, the outer lapping part 22, after being seamed by stitches as 23 to the inner lapping part 24, is bent outwardly and lapped upon itself over the stitches. In thus seaming together the side-crown 10 and brim 16, the edge of the brim 16 comprises the inner lapping part 24, which extends upwardly, while the lower edge of the side-crown 10 comprises the outer lapping part 22, which is lapped upon itself over the stitches 23, this arrangement being adapted to prevent the seepage of water through the seam. In like manner, it will be observed that the top edges of the side-crown piece 10 comprise the inner lapping portions, while the edges of the crown-piece 13 comprise the outer self-lapping portions 22.

Upon the face of the outer lapping portions 22, are secured the parts as 25 of separable snap fasteners, which are adapted to be engaged in the usual manner with other co-operating snap fastener parts as 26, of which there are a sufficient number upon the confronting faces of the self-lapping

portions to provide a choice of engagements therewith. Through these adjusting arrangements, the covering may be made to fit snugly upon straw hats, soft hats, stiff hats and other types.

In Fig. 5, I illustrate the over-lapping portions 22 and 24 connected together by cementing material 27, which not only serves to unite the parts against the seepage of water, but which also reinforces and renders more rigid the overlapping connections. In employing the cemented seam, the parts may be made adjustable as before by using snap fasteners or other suitable sealing devices.

Having thus described my invention, what I claim is:—

1. A covering or hood to protect hats from the elements, made of water-proofed material and comprising a side-crown element, a top-crown element united with the upper edge thereof, a brim element united with the lower edge thereof, and means combined with certain of the said elements to provide for their adjustment relatively with respect to each other.

2. A covering or hood to protect hats from the elements, made of water-proofed material and comprising a side-crown ele-

ment, a top-crown element seamed to the upper edge thereof, a brim element seamed to the lower edge thereof, said seams being of the overlapping character and arranged with the outer lapping portion of the material adjustably lapped upon itself, and means combined with the outer portion of the brim element to provide for the adjustment of the same circumferentially.

3. A covering or hood to protect hats from the elements, made of water-proofed material and comprising a side-crown piece having its ends seamed together, a top-crown piece seamed to the upper edge thereof, a brim piece seamed to the lower edge of the side-crown piece and having its ends seamed together, the seams connecting the side-crown piece with the top-crown piece and also with the brim piece being of the overlapping character and arranged with the outer lapping portions of the material adjustably lapped upon themselves, and fastening devices provided upon the confronting faces of the said outer lapping portions to provide means for effecting their relative connection.

In testimony whereof I have signed my name to this specification.

LIPMAN HENSCHEL.
